UNITED STATES PATENT OFFICE.

MICHAEL CLOONEY, OF ST. LOUIS, MISSOURI, ASSIGNOR OF TWO-THIRDS TO
ROBERT McCULLOCH AND C. NESBIT DUFFY, OF SAME PLACE.

STREET-CAR FENDER.

SPECIFICATION forming part of Letters Patent No. 536,418, dated March 26, 1895.

Application filed December 24, 1894. Serial No. 532,853. (No model.)

To all whom it may concern:

Be it known that I, MICHAEL CLOONEY, of the city of St. Louis, State of Missouri, have invented certain new and useful Improvements 5 in Street-Car Fenders, of which the following is a full, clear, and exact description, reference being had to the accompanying drawings, forming a part hereof.

My invention relates to an improved car 10 fender, and consists in the novel construction, combination and arrangement of parts, hereinafter described and claimed.

The object of my invention is to construct 15 an improved car fender to be applied to street railway cars that will be thrown into engagement with the track whenever the car-brake is applied.

A further object of my invention is to construct a car fender that is extremely simple, 20 inexpensive and easily applied to cars of the present construction without materially altering the trucks of said cars.

In the drawings: Figure 1 is a side elevation of a street car, the same being equipped with 25 my improved fender. Fig. 2 is a plan view of my improved fender, the same being positioned upon the truck-frame, the connections from the fender to the brake being illustrated in this figure. Fig. 3 is a longitudinal sectional view taken approximately on the indicated line 3—3 of Fig. 2 and looking in the direction indicated by the arrow A. Fig. 4 is 30 an enlarged longitudinal sectional view taken approximately on the indicated line 4—4 of Fig. 2 and looking in the direction indicated by the arrow B.

Referring by numerals to the accompanying drawings, 1 indicates the car-body; 2, the truck-frame thereof; 3, the car-axle mounted 40 in suitable bearings fixed to the truck-frame and provided with the usual car-wheels 4.

5, 5 indicate arms that are rigidly bolted to and extend forward from the upper side of the end timber of the truck-frame 2, and are 45 provided with bearings 6 at their forward ends.

A plank or timber 7 is provided with rectangular notches 8 into which the bearings 6 of the arms 5 pass, and occupies a transverse 50 position immediately in front of the end-timber of the truck-frame. This plank or tim-

ber 7 is hinged to the arms 5 by means of a rod 9 that extends longitudinally through the timber 7 through the bearings 6 on the ends of the arms 5, and is provided on the ends of the timber 7 with nuts 10 which rigidly hold 55 said rod in position. Straps 11 pass over the arms 5 and have their ends bolted to the plank 7 adjacent the edges of the rectangular notches 8, thus effectually preventing the rear 6c edge of the plank 7 from swinging too far downwardly.

Bolted to the upper side and at the longitudinal center of the plank 7 is an arm 12, the same being bent into semi-circular form and 65 provided on its end with a weight 13. The function of this weighted arm will presently be shown.

A guard-bar 14 is fixed to and adapted to swing downwardly from the front edge of the 70 timber 7 by means of common strap-hinges 15 fixed to the under side of said guard-bar and said timber 7. The construction of the common strap hinges 15 is such that the guard bar 14 may be moved upward but is prevented 75 from moving downward with relation to the said timber 7, so that said guard bar is normally maintained in the same plane with the said timber. By beveling the front edge of the timber 7 as indicated by 16, the forward 80 edge of this guard-bar 14 may swing into a plane above that occupied by the plank 7.

Securely fixed to the front edge of the guard-bar 14 in any suitable manner and extending forward therefrom are flexible loops 85 17, the same being preferably constructed of short lengths of rubber tubing, such as hose. Said flexible loops are provided on their exteriors with small metallic hooks 18, the object of which will be presently shown. 90

19 indicates an ordinary horizontally extending and moving brake-rod which is provided with a transversely extending arm 20, said arm being adjustable upon the brake-rod 19 by means of a set-screw 21. 95

22 indicates a grooved wheel or pulley, the same being mounted for rotation upon a bearing 23 fixed to the under side of the car body 1.

24 indicates an eye-bolt rigidly secured to 100 the plank 7 adjacent the longitudinal center thereof, and in front of the longitudinally ex-

tending rod 9, which, as will be seen, forms the hinge-pin when the plank 7 swings in any direction.

25 indicates an eye-bolt, the same being rigidly fixed to the plank 7 adjacent the longitudinal center thereof and in the rear of the rod 9.

24^a and 25^a indicate grooved-wheels or pulleys that are fixed to the under side of the car-body directly above the eye-bolts 24 and 25.

26 indicates a rope or cable, one end of which is securely fastened to the eye-bolt 25. From thence it passes vertically upward over 15 the pulley 25^a, from thence rearwardly and around the grooved-wheel or pulley 22; from thence forward to the transverse arm 20, to the end of which it is securely fastened. From the end of said arm, said rope or cable 20 extends forward over the grooved wheel or pulley 24^a, from thence vertically downward, and is secured to the eye-bolt 24 that is fixed near the forward edge of the plank 7.

The operation is as follows: When the car-brake is un-applied and at rest, said brake, through the medium of the rod 19, transverse-arm 20 and rope 26 and also the weighted arm 12, tends to hold the guard-bar 14 and forward end of the plank 7 in an elevated position, the entire fender occupying approximately a horizontal position. Whenever the brake is applied, the brake-rod 19 will necessarily be drawn forward, or in the direction indicated by the arrow C, Fig. 2. The transverse arm 20 being rigidly mounted upon said brake-rod, will necessarily move forward. This draws the rope or cable 26 around the grooved-wheel or pulley 22, over the grooved-wheel or pulley 25^a, and being secured to the eye-bolt 25 will necessarily raise the rear edge of the swinging plank 7. With this forward movement of the brake-rod 19 and transverse arm 20, the rope or cable 26 in front of said transverse arm 20 will move forward over the 45 grooved-wheel or pulley 24^a and allow the forward end of the entire fender to swing downwardly, and the flexible loops 17 on the guard-bar 14 to engage with the track-rails. Thus the swinging movement of the entire fender 50 is equalized and governed entirely by the play of the longitudinally moving brake-rod. When the flexible loops and guard-bar 14 are swung downwardly to engage with the track-rails, should there be any slight obstruction, 55 the flexible loop 17 will give and easily ride over said obstruction. When the fender comes in contact with a body such as that of a person or animal, said body will be either pushed to one side by the fender or caught 60 thereby and carried until the car is brought to a standstill. The hooks 18 upon the flexible loops 17 of the guard-bar 14 tend to catch

and hold some part of the body as it lies upon the fender. The swinging downward of the forward end of the fender takes place every 65 time the brake is applied. Whenever the brake is released, the brake-rod 19 necessarily moves rearwardly, and through the action of the transverse arm 20, rope or cable 26 and weighted arm 12, the fender is brought 70 to its normal position, which is, as heretofore stated, in an approximately horizontal plane. The action of a fender of this construction is positive, as the first act of the driver or person in charge of the car, upon seeing a body 75 upon the track, is to apply the brake. The driver or person in charge of the car, upon seeing a body on the track can devote his entire time and movements to the applying of the brake, as there are no levers, tripping devices or auxiliary parts to occupy his attention in order to throw the fender into position, while the brake is being applied.

A fender of this construction possesses superior advantages in point of simplicity, durability and general efficiency. 85

What I claim is—

1. A car fender, comprising a plank hinged at its transverse center to the forward end of the truck-frame, a guard-bar hinged to the 90 forward edge of the plank, flexible loops fixed to the forward edge of the guard-bar, and a rope or cable fixed to the plank and passing over grooved-wheels or pulleys and attached to the brake-rod, whereby the forward edge of 95 the fender is thrown into and out of engagement with the track.

2. A car fender, comprising a pair of arms fixed to the front rail of the truck-frame, a plank hinged to said arm by means of a longitudinally positioned rod passing through said plank, a guard-bar hinged to the forward edge of the plank, flexible loops provided with metallic hooks fixed to the front edge of the guard-bar, a transverse arm adjustably 105 mounted upon the brake-rod and underneath the car-body, and a rope or cable, the same being secured at any suitable point in its length to the end of the transverse arm, its 110 ends being secured to eye-bolts, one of each of which are positioned upon each side of the center of the plank, forming a part of the fender.

3. In a car fender, a guard-bar hinged to the front edge of the main plank of the fender, and flexible loops provided with hooks fixed to and extending forward from the front edge of said guard-bar. 115

In testimony whereof I affix my signature in presence of two witnesses.

MICHAEL CLOONEY.
